UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

FOLDER FOR SEWING-MACHINES.

1,167,777.

Specification of Letters Patent.

Patented Jan. 11, 1916.

Application filed February 26, 1912. Serial No. 679,979.

To all whom it may concern:

Be it known that I, JAMES R. MOFFATT, a citizen of the United States, residing at Chicago, in the county of Cook, State of Illinois, have invented certain new and useful Improvements in Folders for Sewing-Machines, of which the following is a description, reference being had to the accompanying drawing, and to the letters and figures of reference marked thereon.

The invention relates to new and useful improvements in folders for sewing machines, and more especially to the type of folder which folds a strip of fabric longitudinally intermediate its side edges, and inverts the strip as it is delivered to the stitching mechanism.

An object of the invention is to provide a folder which is so constructed that it is capable of folding a strip with one side face of the strip much wider than the other, and the inverting and delivering of the strip to the stitching mechanism.

A further object of the invention is to provide a folder of the above character, with a separating device for separating and supporting the upper face of the binding strip, as it passes from the folder to the stitching mechanism, whereby a free space is formed beneath said separating plate, for a body fabric so that an elastic fabric may be led beneath said separating plate to the stitching mechanism, where the binding strip is applied to the elastic fabric, without stretching of the elastic fabric.

These and other objects will in part be obvious, and will in part be hereinafter more fully described.

In the drawings which show by way of illustration one embodiment of the invention: Figure 1 is a perspective view, showing a folder having my improvements applied thereto, and also the arrangement of the folder relative to the stitching mechanism, and the devices for feeding the folded strip and body fabric to the stitching mechanism; Fig. 2 is a perspective view showing the manner of folding a strip and positioning the same relative to a body material, to which it is to be stitched; Fig. 3 is a sectional view through the folder on the line 3, 3, of Fig. 1; Fig. 4 is an end view of the receiving end of the folder; Fig. 5 is an end view of the delivery end of the folder,

the separating plate being removed, and the supporting shank for the folder sectioned.

In carrying out the invention, I have provided a folder which is attached to a supporting shank 1, that may be screwed or otherwise secured to the bed plate of the machine. Said folder consists of spaced plates 2 and 3, which are arranged at their receiving end so as to form an L-shaped passage 4, one part of which is substantially horizontal, and the other part of which is substantially vertical. The vertical portion of said passage 4, is much shorter than the horizontal portion. The plate 2, at the receiving end of the folder, extends beyond the plate 3, and a tension finger 5 is adapted to bear against the strip as it passes along the plate 2. Said tension finger is formed with an opening through which passes a post 6, around which is placed a spring 7. Said spring bears against the finger to press the same against the material passing through the folder. The tension of the spring 7 is controlled by suitable nuts. The plates 2 and 3 as they approach the delivery end of the folder, are shaped so as to fold the edge of the strip back upon the body portion of the strip.

The plate 2 at the delivery end of the folder, extends around the edge of the plate 3, and forms the folding passages 8, 8, for the edges of the fabric. The plates 2 and 3 are also gradually bent so as to fold the fabric intermediate its edges, as clearly shown in Fig. 5. This bent portion in the plates 2 and 3, is so disposed that one face of the folded strip is much wider than the other face of the folded strip. The folder is attached to the sewing machine so that the longitudinal axis of the folder is at right angles to the line of feed. The folded strip as it leaves the delivery end of the folder, is therefore, inverted as it passes to the stitching mechanism in a manner well known in this type of folder. This inverting of the folded strip brings the folded edges of the strip against the faces of the body material.

In Fig. 2, I have shown a strip of fabric 9, the edges of which at 10 and 11, are folded back upon the body part of the strip, and the strip is folded intermediate its edges 105 as at 12, so that when the strip is inverted and positioned relative to a body fabric 13, there is a relatively narrow face 14 on the

upper side of the fabric, and a relatively wide face 15 on the lower side of the fabric. As shown in Fig. 1, this binding strip is adapted to be secured to the body fabric by lines of stitching which pass through the folded edges of the binding strip.

In order to guide the folded strip as it leaves the delivery end of the folder, I have provided fingers 16 and 17, which are mounted at the extreme delivery edges of the plates 2 and 3. Said fingers serve as a guide for the edge of the strip as it is inverted and led from the folder. In order to further guide the strip as it passes to the stitching mechanism, I have provided an edge guide 18 which is located in rear of the folder and is adjustably secured to the shank supporting the folder, by screws 20 which pass through a slotted shank 21 connected to the edge guide. Said edge guide 18 is formed with an overhanging lip 22.

In order to support the upper edge of the binding strip, and hold the same away from the lower part of the folder, I have provided a separating plate 23 which is pivoted at 24 to a block 25, carried by the shank of the folder. This separating plate is formed with an arc-shaped slot 26, and a pin 27 carried by the block, enters said slot and limits the swinging movement of said separating plate. Said separating plate is adapted to extend underneath the overhanging lip 22 of the edge guide. The upper face of the binding strip will be supported by this separating plate, and thereby a free passage is formed underneath the separating plate, so that an elastic fabric may be led through said passage, without any retarding effect of the folder on said elastic fabric. The block 25 may serve as an edge guide for the elastic fabric. This separating plate, together with the edge guide and overhanging lip, also serves to maintain the fold in the edge of the strip as it passes to the stitching mechanism. There is between the delivering end of the upper edge of the folder and the presser foot considerable distance. Unless means is provided for maintaining the fold in the edge of the fabric, it will uncurl before it reaches the presser foot. The means above referred to accomplishes this result.

In Fig. 1 of the drawings, I have shown the arrangement of the binder relative to the presser foot 28 of the sewing machine. Said binder is so positioned as to extend in front of the presser foot, and deliver the folded binding strip underneath the presser foot. The edge guide 18 extends into a notch at the forward end of the presser foot, so that the edge of the binding strip is guided until it has passed underneath the presser foot. This edge guide and overhanging lip 22 serve as a means for maintaining the folded-over edge of the binding

strip, and presenting the same to the upper face of the body fabric. The folder is preferably positioned slightly in front of the presser foot, so that a differential feed foot may operate upon the elastic material only 70 in advance of the presser foot.

From the above description, it will be apparent that I have provided a folder which is capable of folding a strip of fabric, turning in the raw edges thereof, and presenting 75 said strip to the stitching mechanism, so that when the strip is stitched to a body fabric, one of its faces will overlap the body fabric to a greater extent than the other, thereby forming a facing strip for the body 80 fabric and a binding for the edge of the body fabric.

It is obvious that minor changes in the details of construction may be made, without departing from the spirit of the invention as set forth in the appended claims. 85

Having thus particularly described my invention, what I claim as new and desire to secure by Letters Patent, is:—

1. A folder for sewing machines, said folder including a body portion having spaced guiding walls shaped so as to fold a strip between its edges, said folder being located at an angle to the line of feed and having its delivery end cut away, whereby said strip may be inverted, said folder at one side of the central plane thereof being wider than at the other, so that one face of the folded strip when guided through the folder may be wider than the other, and means independent of the folder extending between the faces of the folded strip after it leaves the folder for guiding and maintaining the fold in said strip. 90 95 100

2. A folder for sewing machines, said folder including a body portion having spaced guiding walls shaped so as to fold a strip between its edges, said folder being located at an angle to the line of feed and having its delivery end cut away, whereby said strip may be inverted, said folder at one side of the central plane thereof being wider than at the other, so that one face of the folded strip when guided through the folder may be wider than the other, means independent of the folder extending between the faces of the folded strip after it leaves the folder for guiding and maintaining the fold in said strip, and means for placing a tension on the strip as it passes into the folder. 110 115 120

3. A folder for sewing machines, including means for folding a strip with one face thereof wider than the other, and for inverting said folded strip whereby the same is led from the folder in a direction at an angle to the longitudinal axis of the folder, and a separating plate for supporting the upper folded edge of the strip after the same passes from the folder. 125 130

4. A folder for sewing machines, including means for folding a strip with one face thereof wider than the other, and for inverting said folded strip whereby the same is led from the folder in a direction at an angle to the longitudinal axis of the folder, and a separating plate for supporting the upper folded edge of the strip after the same passes from the folder, means for 10 pivotally supporting said separating plate, and a stop for limiting the swinging movement thereof.
5. A folder for sewing machines, including means for folding a strip with one face 15 thereof wider than the other and for folding in the edges of the strip, and for inverting said folded strip whereby the same is led from the folder in a direction at an angle to the longitudinal axis of the folder, and a separating plate for supporting the 20 upper folded edge of the strip as it passes
- from the folder, said separating plate being spaced from the lower part of the folder, whereby a body fabric may be led underneath said separating plate. 25
6. A folder for sewing machines, including means for folding a strip with one face thereof wider than the other, and means for inverting said folded strip, whereby it may be led from the folder in a direction at an 30 angle to the longitudinal axis of the folder, an overhanging lip for maintaining the edge folded after it leaves the folder, and a separating plate extending underneath said overhanging lip for supporting the 35 folded edge after it leaves the folder.

In testimony whereof I affix my signature, in presence of two witnesses.

JAMES R. MOFFATT.
